US0D1076238S

(12) **United States Design Patent** (10) **Patent No.:** **US D1,076,238 S**
(45) **Date of Patent:** **** May 20, 2025**

(54) **EARMUFF**

(71) Applicant: **Shenzhen Thousandshores Technology Co., Ltd.**, Shenzhen (CN)

(72) Inventors: **Ding He**, Shenzhen (CN); **Xu Feng Yang**, Shenzhen (CN); **Jia Ting Xiao**, Shenzhen (CN); **Ming Li**, Shenzhen (CN)

(73) Assignee: **SHENZHEN THOUSANDSHORES TECHNOLOGY CO., LTD.**, Shenzhen (CN)

(**) Term: **15 Years**

(21) Appl. No.: **29/917,054**

(22) Filed: **Nov. 16, 2023**

(51) LOC (15) Cl. **29-02**

(52) U.S. Cl.

USPC **D29/112**; D14/205

CLAIM

The ornamental design for an earmuff, as shown and described.

DESCRIPTION

FIG. 1 is a front, top perspective view of an earmuff, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the earmuff that form no part of the claimed design.

1 Claim, 8 Drawing Sheets
